BOAT

Filed Sept. 28, 1921

UNITED STATES PATENT OFFICE.

CHARLES R. TWITCHELL, OF LOS ANGELES, CALIFORNIA.

BOAT.

Application filed September 28, 1921. Serial No. 503,956.

To all whom it may concern:

Be it known that I, CHARLES R. TWITCHELL, a citizen of the United States, residing at Los Angeles, in the county of Los Angeles and State of California, have invented new and useful Improvements in Boats, of which the following is a specification.

This invention relates to a boat, and particularly pertains to a sectional boat of the 10 row-boat or skiff type.

An object of this invention is to provide a sectional boat which may be readily set up and knocked down, and embodying a connection for separable parts which is so 15 constructed as to form a strong and watertight joint.

Another object is to provide a boat having transversely separable sections formed of sheet metal adapted to be detachably 20 connected together in which the sheet metal of the sections is so formed as to form reinforcements to produce a structure of considerable strength and light in weight.

A further object is to provide an effective 25 means for adjoining adjacent sections which will insure against leakage at the joint and also afford a transverse reinforcement to the structure.

Other objects will appear hereinafter.

30 The invention is illustrated in the accompanying drawings, in which:

Figure 1 is a plan view of a boat constructed in accordance with this invention, showing it as assembled.

35 Figure 2 is a side view of same with parts broken away.

Figure 3 is a view in cross section as seen on the line 3—3 of Figure 1.

Figure 4 is a detail in cross section as seen 40 on the line 4—4 of Figure 1.

Figure 5 is a detail in section as seen on the line 5—5 of Figure 3.

Figure 6 is a detail in perspective, illustrating the separable connections between 45 the adjacent sections as formed at the rail of the boat showing them in a separated position.

Figure 7 is a detail in section and perspective of a gasket for sealing the joint.

50 Figure 8 is a detail in section showing the manner of forming the joint between the bottom and side portions of the boat.

The invention is here shown as applied to a row-boat of the flat bottom, double 55 prow type, and divided transversely intermediate its ends into two hull sections A

and B, each of which embodies a bottom panel 10 and side panels 11 and 12. The bottom panel is formed straight across one end and has its side edges converging to a point, and the side panels 11 and 12 are connected to the converging edges of the bottom panel at a slight inclination and extend from the straight end of the bottom panel to their intersection in the prow.

As a means for reinforcing the bottom panel longitudinally, the sheet metal of which it is formed is pressed to form ribs 13, and to further strengthen the structure and at the same time afford a water tight 70 joint between the side panel and the bottom panel, a double seamed joint 14 is employed, as shown in Figure 8, that is the lower edge of the side panel is turned outwardly and upwardly forming an up-turned flange 15, and the outer edge of the bottom panel is turned upwardly over the outer face of the flange 15 and then turned inwardly and downwardly forming a flange 16 extending between the flange 15 and the outer face of the side panel; the joint thus formed being rolled to effect a seal and at the same time provide a longitudinal rib at the juncture of the side and bottom panels to serve as a reinforcement. The upper edges of the side 80 panels are turned outwardly and then inwardly to form hollow or tubular rails 17 which are sealed; the open ends of the tubular rails being closed by blocks or plugs 18 and 19, as particularly shown in Figure 5. 90 The tubular rails constitute air compartments which serve to give sufficient buoyancy to the boat to prevent its sinking in event it becomes filled with water.

The inner end portion of one of the hull sections is formed sufficiently larger than the inner end portion of the other hull section, so that when the two sections are placed end for end in their assembled position, the end of one section will overlap 100 the end of the other section. To permit the end of the tubular rail 17 on one section to telescope the rail on the adjacent section the lower portion of the outermost rail is removed, as indicated at 20 in Figure 6; 105 the upper portion of the rail forming a flange 21 adapted to extend over the upper portion of the adjacent rail, which flange is formed with an opening 22 adapted to register with a corresponding opening 23 on 110 the inner rail through which a screw 24 may be passed and engaged with the block

18, as shown in Figure 5. For similar reasons the end portions of the double seamed joints 14 are cut away on the smaller hull section to permit it to telescope the larger section. The overlapping portions of the bottom and side panels are formed with registering openings 25 and 26 through which machine screws 27 may be passed and screwed into engagement with a demountable clamping strip 28, which strip preferably comprises a single piece formed to extend transversely across the bottom panel and up the inner face of the side panels over the tubular rails, and is formed with threaded openings to register with the openings 25-26 and with unthreaded openings registering with the openings 22-23.

As a means for tightly sealing the joint between the overlapping portions of the boat section, a gasket 30 is employed which is preferably constructed as illustrated in Figure 7, and comprises a flattened rubber tube 31 adapted to extend throughout the length of the joint and formed with openings 32 through which the screws may pass.

In assembling the boat, the sections A and B are placed end to end, as shown in Figure 1, with adjacent end portions overlapping and with the gasket 30 interposed between the overlapping portions. The strip 28 is then set in place and the machine screws 27 inserted through the registering openings 25-26 and 22-23 and screwed into engagement with the threaded openings, as shown in Figure 4, thus securely fastening adjacent ends of the boat sections together. The screws 24 pass through openings in the end portion of the strip and screw into engagement with the plug 18, as shown in Figure 5, to securely fasten the ends of adjacent tubular rails together.

From the foregoing it will be seen that I have provided a sectional boat which may be readily assembled or taken apart, and in which the parts when separated may be meshed together to form a compact package convenient for transportation and storage, and which when assembled will form a structure of great strength and lightness; the ribs 13, seam 14 and rails 17 serving to strengthen the boat against longitudinal bending and the clamp strip 28 acting to strengthen the hull transversely.

While I have shown and described a spe-

cific embodiment of my invention, I do not limit myself to the exact details of construction shown, but may employ such changes in construction and modification of parts as come within the scope of the appended claims.

I claim:

1. In a sectional boat, a plurality of hull sections, each embodying side panels, a tubular rail formed on the upper edges of the side panel forming air chambers, the panels of adjacent sections being adapted to overlap each other, the tubular rails of one of the sections being cut away to receive the ends of the rails of the adjacent section and having portions adapted to overlap the adjacent rails, and means for detachably connecting the overlapped portions of the rails together.

2. In a sectional boat, a plurality of hull sections, each embodying side panels, a tubular rail formed on the upper edges of the side panel forming air chambers, the panels of adjacent sections being adapted to overlap each other, the tubular rails of one of the sections being cut away to receive the ends of the rails of the adjacent section and having portions adapted to overlap the adjacent rails, the overlapped portions of said rails formed with openings, blocks in the innermost rails opposite the openings, and screws insertable through said openings and engageable with said blocks for connecting said rails together.

3. A sectional boat comprising a plurality of telescoping metal hull sections having bottom and side panels assembled with interlocking double turned joints; the upper edges of said side panels turned to form an air chamber gunwale; and means for making water tight connections between said sections; said joints and said rails being adapted for longitudinally reinforcing said sections.

4. In a sectional boat a plurality of sheet metal hull sections adapted to be detachably secured together said sections comprising a flat corrugated bottom plate and a pair of side panels secured to said bottom plate, the upper edge of each of said side panels turned to form an air chamber gunwale.

CHARLES R. TWITCHELL.
